FIG. 1 is a reduced front elevational view of an edge supporting brace for display panels showing my new design, with the broken line showing for illustrative purposes only and forming no part of the claimed design;

FIG. 2 is an isometric view of the design;
FIG. 3 is a front elevation view of the design;
FIG. 4 is a rear view thereof;
FIG. 5 is a top view thereof;
FIG. 6 is a bottom view thereof;
FIG. 7 is a right side view thereof; and,
FIG. 8 is a left side view thereof.

CLAIM

The ornamental design for a edge supporting brace for display panels, as shown and described.

DESCRIPTION

FIG. 2

FIG. 1

FIG. 3

FIG. 4

FIG. 5

FIG. 6

FIG. 7

FIG. 8
